UNITED STATES PATENT OFFICE.

CHARLES A. LINDSTRÖM, OF PITTSBURG, PENNSYLVANIA, ASSIGNOR TO PRESSED STEEL CAR COMPANY, OF PITTSBURG, PENNSYLVANIA, A CORPORATION OF NEW JERSEY.

CAR-DOOR MECHANISM.

No. 902,749.

Specification of Letters Patent.

Patented Nov. 3, 1908.

Application filed April 15, 1908. Serial No. 427,193.

To all whom it may concern:

Be it known that I, CHARLES A. LINDSTRÖM, of Pittsburg (North Side,) Allegheny county, Pennsylvania, have invented certain new and useful Improvements in Car-Door Mechanism, of which the following is a full, clear, and exact description, reference being had to the accompanying drawings, in which like characters refer to like parts, and in

10 which—

Figure 1 is a plan view of substantially one-fourth of a car embodying the present invention, a portion of the side flange being removed for clearness; Fig. 2 is a sectional 15 side elevation of the same; Fig. 3 is a detail transverse section through the car looking toward the end, showing relative position of the parts when the doors are closed; Fig. 4 is a like view, the doors being open; Fig. 5 is 20 a like view showing the doors closed, the latch about to be operated, and Fig. 6 is a like view showing modifications of structure.

An object of the present invention is to provide a modification of the structure shown 25 and described in my application for Letters Patent, entitled "Car door operating mechanisms", filed November 20, 1907, Serial No. 402,989, in which a door operating and locking mechanism is disclosed, comprising a 30 door-closing shaft with suitable levers or arms thereon to raise the doors, door-locking shaft movable bodily into door locking position and suitable connections between the two shafts whereby they are operated in 35 proper sequence.

In the present structure, the door operating shaft is not bodily movable but instead a system of latches is provided adapted to be thrown into locking position which exercises 40 a final lifting force on the doors after the doors have been closed by their operating arms or levers.

Referring now in detail to the drawings, 1 represents the car body, 2 the end sill, 3 the 45 door operating shaft, 4 the door lifting arms carried thereby, 5 the doors, 6 wearing shoes mounted on the underside of the doors.

7 is an arm rigidly mounted on operating shaft 3, 8 is a link for operating arm 7, 9 is a 50 gear for operating link 8 having a stop 10 thereon against which link 8 rests to prevent excess movement of gear 9 when the latches herein described have been thrown to the limit of their inward movement.

11 is an operating lever carrying pinion 12 55 operated by pawl 13 mounted on lever 11.

14 is a pawl mounted on frame 15 which frame 15 is rigidly secured to end sill 2.

17 is a gear operated by pinion 12 and loosely mounted on shaft 18. Integral with 60 gear 17, and hence also loosely mounted on shaft 18, is a gear 19 which meshes with and drives gear 9.

20 is an arm rigidly mounted on shaft 18 and carrying a pin 21 adapted to engage a 65 notch 22 formed in the peripheral surface 9^a in gear 9 and having a projecting abutment or nose 9^b on one side thereof.

23 are pinions rigidly mounted on shaft 18 and meshing with teeth of latches 24. The 70 latches 24 are slidably mounted in guides 25 and riveted or secured to the side edge plate or strip of the car frame or to other suitable portion of the car-side structure.

26 are cam shoes in line with latches 24, 75 both latches 24 and shoes 26 are provided with oppositely inclined engaging faces. There may be any suitable number of latches for each of the doors.

The operation of the structure thus far described is as follows:—Suppose the doors to be open as shown in Fig. 4, the pawl 13 is thrown to the position as shown in Fig. 3 and the lever 11 operated toward the side of the car. This will turn pinion 12 in the direction 80 of the arrow, (Fig. 4), gear 17 in the opposite direction, and gear 9 in the same direction as pinion 12. Gear 17 being loosely mounted on shaft 18, no motion is communicated to

said shaft 18. As gear 9 rotates pin 21 carried by arm 20 slides over the peripheral surface 9^a, at the same time link 8 is drawn upwardly turning shaft 3 and through the medium of arms 4 bearing on shoes 6, the doors are elevated to the position shown in Fig. 5. 90

At the moment the doors reach the position shown in Fig. 5, pin 21 on arm 20 strikes the projecting abutment or nose 9^b and is forced into notch 22, whereupon arm 20 is locked to gear 9 which as it continues to turn through 95

arm 20 rotates shaft 18, and pinions 23 throwing all of the latches 24 forward into engagement with their respective shoes 26. As latches 24 cannot be deflected downwardly, doors 5 must be forced upwardly 100

into snug, closed position, thus preventing escape of lading around the periphery of the door. Meanwhile, during the movement of 105

the latches the link 8 passes the center of gear 9 and strikes stop 10 which prevents further movement of gear 9. This final movement having the effect of lowering the arms 4 from engagement with shoes 6, thus effectively taking the weight of the doors from the door-lifting means and throwing the entire weight of the doors and lading upon the door hinges and latches. To open 10 the doors, the pawl is reversed and the lever is moved in an opposite direction and notch displacing pin 21 and arm 20, thus rotating shaft 18 in the opposite direction and hence elevating arm 20 to lift it from notch 22 onto 15 the peripheral surface 9^a. When pin 21 reaches the peripheral surface 9^a the latches have been withdrawn from locking positions and link 8 has again passed its dead center and instantly the weight of the lading on the 20 doors forces them downwardly, arms 4 being depressed, shaft 3 rotated and gears 9, 19 and 17 and pinion 12 running away from lever 11, the teeth of pinion 12 passing freely beneath the pawl 13.

25 In Fig. 6 is shown a modification of the structure already described wherein a cam notch 27 is formed in the latch 24 instead of in the cam gear 9. In this case a small gear or pinion 28 is rigidly mounted on the shaft 30 18 and meshes directly with the teeth of the gear wheel 9, the operation of the mechanism being substantially the same.

Having thus described my invention, the following is what I claim to be new therein 35 and desire to secure by Letters Patent:

1. In a car door mechanism, a drop door, a latch slidably mounted on the car underframe adjacent the edge of said door and a rotatable shaft for projecting said latch into 40 door-locking position.

2. In a car door mechanism, a plurality of drop doors, a plurality of latches slidably mounted on the car underframe adjacent the edges of said doors and a rotatable shaft for 45 projecting said latches into door-supporting positions.

3. In a car door mechanism, a door and means for operating said door, a suitably mounted slidable latch having a cam surface 50 and adapted to engage said door and exert a final closing pressure thereon.

4. In a car door mechanism, a door and means for operating said door, a slidable latch mounted on the edge of the car side in front 55 of said door and having a cam surface, said latch being adapted to engage said door and exert a final closing pressure thereon and means for operating said latch.

5. In a car door mechanism, a door and 60 means for operating said door, a rotatable shaft and a slidable latch mounted on the car underframe in front of said door, geared to said shaft and adapted to be projected thereby into door locking position.

6. In a car door mechanism, a door, and

means for operating said door, a cam-faced shoe on said door, a cam-faced slidable latch in line with said shoe and means for projecting said latch to throw it into engagement with said shoe to exert a final closing pressure on said door. 70

7. In a car door mechanism, a drop door, and a latch slidably mounted on the car underframe beneath the car side and in front of said door and means for operating said latch. 75

8. In a car door mechanism, a door, means for operating said door, a slidable latch mounted on the car underframe in front of said door, and an intermittent gear interposed between said latch and door-operating 80 means.

9. In a car door mechanism, a door, a gear for operating said door, a slidable latch, a shaft geared to said latch and an intermittent gear interposed between said shaft and 85 door gear.

10. In a car door mechanism, a door, arm for raising said door, a slidable latch adapted to exert a final closing pressure on said door and disengage said door from said raising arm 90 and means for operating said mechanism.

11. In a car door mechanism, a door, an arm for raising said door, a slidable latch having a cam surface, a shoe on said door in line with said latch, means for operating said 95 door-raising arm and projecting said latch, said latch being adapted to strike said shoe and exert a final closing pressure on said door to disengage the door from said arm.

12. In a car door mechanism, a drop door, and a latch slidably mounted on the car underframe beneath the car side, a rotatable shaft also mounted beneath the car side and geared to said latch for projecting same into 100 door-supporting position.

13. In a car door mechanism, a door, an arm for raising said door, a cam wheel geared to said arm, a slidable latch, a shaft for operating said latch, an arm carried by said shaft in engagement with said cam wheel and 110 means for operating said mechanism.

14. In a car door mechanism, a door and means for operating said door, a slidable latch mounted beneath the car side, suitable guides for said latch and a rotatable shaft for 115 operating said latch.

15. In a car door mechanism, a door extending between the center and the side of the car, means for operating said door, a slid- 120 able latch for said door mounted beneath the car side and a rotatable shaft for projecting said latch across the edge of said door into locking position.

16. In a car door mechanism, a drop door, means for operating said door, a plurality of sliding latches mounted on the car underframe adjacent the edge of said door and a rotatable shaft for projecting said latches simultaneously across the edge of said door 125 into locking positions. 130

17. In a car door mechanism, a plurality of drop doors, means for simultaneously operating said doors, a plurality of sliding latches mounted on the car underframe adjacent the edges of said doors and a rotatable shaft for simultaneously projecting said latches across the edges of said doors into locking positions.

18. In a car door mechanism, a drop door, means for operating said door and a latch having a door-engaging surface disposed at

an angle with relation to said door and means for projecting said latch to cause said surface to exert a final closing pressure on the door.

The foregoing specification signed at Mc-¹⁵
Kees Rocks, Allegheny county, Pennsylvania, this 6th day of April, 1908.

CHARLES A. LINDSTRÖM.
